EARRING OR THE LIKE

Charley E. Dale, Charles L. Mull, and Wilton Avirett, Seattle, Wash.

Application September 24, 1954, Serial No. 32,433

Term of patent 14 years

(Cl. D45—9)

FIG. 1

FIG. 2

FIG. 3

Figure 4 is a modified top plan view of the same in which the pendant is moved to the side to improve the clarity of illustration.

We claim:

The ornamental design for an earring or the like, as shown and described.
